DESIGN FOR AN AUTOMOBILE EMBLEM

Harvey J. Monette, East Templeton, Mass.

Application August 14, 1941, Serial No. 102,846

Term of patent 14 years

To all whom it may concern:

Be it known that I, Harvey J. Monette, a citizen of the United States, residing at East Templeton, in the county of Worcester and State of Massachusetts, have invented a new, original, and ornamental Design for an Automobile Emblem, of which the following is a specification, reference being had to the accompanying drawing, forming part thereof.

Fig. 1 is a view in front elevation; and

Fig. 2 is a view in side elevation of an automobile emblem showing my new design.

The drawing is shaded for color, and the rear of the emblem is plain.

The characteristic features of my design are represented in full lines in the drawing.

I claim:

The ornamental design for an automobile emblem, as shown and described.

HARVEY J. MONETTE.
